UNITED STATES PATENT OFFICE.

WILLIAM E. KINNEAR, OF FREMONT, OHIO.

THILL-COUPING.

SPECIFICATION forming part of Letters Patent No. 239,255, dated March 22, 1881.

Application filed November 13, 1880. (No model.)

To all whom it may concern:

Be it known that I, WILLIAM E. KINNEAR, of Fremont, in the county of Sandusky and State of Ohio, have invented a new and valuable Improvement in Thill-Couplings; and I do hereby declare that the following is a full, clear, and exact description of the construction and operation of the same, reference being had to the annexed drawings, making a part of this specification, and to the letters and figures of reference marked thereon.

Figure 1 of the drawings is a side view. Fig. 2 is a horizontal section.

This invention relates to devices for attaching thills and poles to vehicles.

It consists in the construction hereinafter described.

In the annexed drawings, A is the carriage-axle; B, the clip. Projecting in front from clip 20 B are the ears D D, one of which is integral with said clip, and the other is attached thereto by a rule-joint, d. In the ends a of said ears are bored holes E, and on the inside of said ears, back of holes E, are formed recesses or 25 seats F, one in each ear, the holes and recesses being opposite each to each when the ears are in position. Seated at the bottom of each recess F is a stud, H, made of hard metal, which is inserted into the ear and made fast therein. 30 I is the shaft-iron, having head K, said head having curved ends L L, of a size and shape to snugly fit recesses F. In the points of ends L L are depressions l l, of a size and shape to snugly fit the projecting inner ends of studs H H.

Through holes E E is a screw-bolt, M, one of said holes being threaded to correspond with the threads on the bolt.

In connecting the thills or pole to the vehicle, the head K is placed with its ends L L 40 resting in recesses F F, with the studs H H bearing in depressions l l. The bolt M is then run through holes E E, and by turning upon its end the whole is made fast. To compensate for any slight wear, the bolt M can be 45 tightened up.

In constructing the recesses F F, studs H H, and ends L L, with their depressions l l, the aim is to give them such a shape and fit that the greater part of the wear will come upon 50 the studs, which act as pintles on which the shaft-iron turns. As these studs become worn they can be readily backed out and new ones inserted in their place.

What I claim is—

The combination of ears D D, one rigid with, 55 the other hinged to, the clip B, and having holes E E, one being threaded, and recesses F F, hard-metal studs H H, made fast in said recesses, head K, having depressions l l in its 60 ends L L, and screw-bolt M, all constructed and arranged as and for the purpose described.

In testimony that I claim the above I have hereunto subscribed my name in the presence of three witnesses.

WILLIAM ERVIN KINNEAR.
